UNITED STATES PATENT OFFICE.

ISAAC A. RYAN, OF IRENTON, OHIO.

GRAPPLING YOKE FOR HANDLING AND CONVEYING WIRE BALES AND THE LIKE.

Application filed May 8, 1924. Serial No. 711,799.

To all whom it may concern:

Be it known that I, ISAAC A. RYAN, a citizen of the United States of America, residing at Ironton, in the county of Lawrence 5 and State of Ohio, have invented certain new and useful Improvements in Grappling Yokes for Handling and Conveying Wire Bales and the like, of which the following is a specification.

10 This invention relates to certain new and useful improvements in grappling yokes especially designed for the handling and conveying of wire bales and the like for conveying the wire bale to a bath for treatment 15 prior to the forming of the wire into nails, and is also capable for conveying rods or plates.

20 The primary object of the invention is to provide a grappling yoke preferably suspended from the chain of a crane wherein the yoke hooks or arms are pivotally supported upon a cross bar having keeper hooks manually releasable and adapted for cooperation with the arms for locking the same 25 in bale or bar suspending position.

With the above and other objects in view that will become apparent as the nature of the invention is better understood, the same 30 consists of the novel form, combination and arrangement of parts hereinafter more fully described, shown in the accompanying drawings and claimed.

35 In the drawings, wherein like reference characters designate corresponding parts throughout the same,

40 Figure 1 is a side elevational view of a grappling yoke constructed in accordance with the present invention, a bale of wire illustrated by dotted lines shown as supported thereby,

Figure 2 is a side elevational view of the grappling hook in its released position,

Figure 3 is a top plan view,

Figure 4 is an end elevational view,

45 Figure 5 is a vertical cross-sectional view taken on line V—V of Fig. 1 showing the chain hook of the crane released from the bracket bar of the grapple and lowered into engagement with the conical block of the 50 grapple to laterally displace the chain hook with respect to the suspending bracket bar,

Figure 6 is a vertical cross-sectional view taken on line VI—VI of Fig. 1,

55 Figure 7 is a horizontal sectional view taken on line VII—VII of Fig. 1 showing

the overlapping ends of the suspending arms of the grapple, and

Figure 8 is an elevational view showing spaced grapple yokes suspending rods or plates.

60 The grappling yoke embodies a cross head formed of spaced channel bars 1 having outwardly directed flanges 2 at the upper and lower edges thereof, the side bars 1 being connected together in spaced relation by blocks 3 positioned at the ends thereof and extending above the bars as at 3^a. A pair of spacing blocks 4 is positioned between the bars 1 at points spaced from the ends of the bars and have the ends of an inverted 70 substantially V-shaped bracket rod 5 anchored therein that extends above the cross-head as shown in Figs. 1, 2 and 5. A centrally positioned block 6 having a tapering head 7 is secured as at 8 between the spaced 75 side bars 1 and is disposed directly beneath the apex of the bracket rod 5. The grappling yoke is adapted to be suspended by the hook 9 carried by the lower end of the chain 10 depending from a crane with the hook 9⁸⁰ engaging the bracket rod 5 for elevating and moving the grappling yoke.

85 A pair of grappling arms are pivotally supported between the spaced side bars 1, each grappling arm being of angle formation and embodying leg portions 11 and 12, a grappling arm being associated with each 90 end of the cross head and being pivotally supported upon the pin 13 extending between the lugs 14 that are carried by the 95 brackets 15 which are secured as at 16 to the lower flanges 2 of the side bars, the upper cam-shaped end 11^a of the leg portion 11 of each grappling arm extending above the side bars 1 when the leg portion 11 is vertically positioned as shown in Fig. 1.

100 A keeper loop is pivotally supported upon the cross head at each end thereof for cooperation with the longer edge of the upper end portions of the grappling arms to hold the lower leg portions 12 in elevated closed position as shown in Fig. 1, the keeper loops, as shown in Fig. 3, embodying side legs 17 connected by cross heads 18 having cam-shaped lower faces at their free ends 105 while the other ends thereof enclose the upper ends 3^a of the spacing blocks 3 and are pivotally connected thereto by the pins 19, the side legs 17 of each keeper loop enclosing the upper end portion of the leg portion 110

11 with one end portion engaging the cross head 18 to hold the grappling arms against pivotal movement upon the pins 13. To release the keeper loops from the upper ends 5 of the grappling arms, each keeper loop is provided with a lateral projection 20 having an opening 21 formed therein adapted to receive a rod 22 that is manually positioned therein for pivoting the keeper loop upon 10 its pin 19 for elevating the cross head 18 to disengage the same from the upper end portion of the leg portion 11 of the grappling arm, the overbalanced lower leg portions 12 and weights supported thereby causing a 15 pivotal movement of the grappling arms and a consequent release of an article supported thereby. The meeting ends of the leg portions 12 are cutaway as at 12^a to provide a continuous overlapping connection for the 20 leg portions 12 as shown in Fig. 7 and to facilitate the raising of the leg portions 12 to their upper closed and locked positions, lateral projections 23 having openings 24 therein receive the manually operable rods 25 22 to effect pivotal movement of the grappling arms and the elevation thereof to their locked position. When the grappling arms are manually elevated to their grappling positions, the cam-shaped ends 11^a 30 of the leg portions 11 engage the cam-shaped lower faces of the cross heads 18 for lifting the keeper loop to permit the end portions of the legs 11 to pass below the cross heads 18. The keeper loops will then fall and lock 35 the grappling arms in their operative position.

In the art of nail-making, wire in bale form as indicated by the reference character B in Figs. 1 and 2 is treated by different methods, 40 such as immersion in a bath to remove scale from the surface of the wire and also as a preliminary step in the tempering thereof, the grappling yoke disclosed in this application being designed for transporting 45 the bale as indicated in Fig. 1. The chain hook 9 depending from a crane engages the upper end of the bracket rod 5 and with the bale B supported by the leg portions 12 of the grappling arms, the bale is transported 50 from one place to another. When it is desired to release the bale from the grappling yoke, the handle rods 22 are manually positioned in the apertured extensions 20 of the keeper loop to elevate the same upon their 55 pivot pins 19 to free the cross head 18 of the keeper loops from the upper ends 11^a of the leg portions 11 of the grappling arms, the weight of the arms and the bale B supported thereby automatically moving the 60 grappling arms upon their pivotal mountings 13 to discharge the bale therefrom. In closing the arms to their elevated and locked position as shown in Fig. 1, and with a bale B gripped therein, the handle rods 22 engage the apertured projections 23 upon the 65

lower portions of the leg sections 11 to move the same upon their pivotal mountings 13 and the cooperating beveled faces of the end 11^a and the cross head 18, the keeper loop is automatically moved to a locking position 70 with respect to the grappling arms. Further employment of the grappling yoke in a different manner is suggested in Fig. 8 wherein rods or plates A are supported at their ends in pairs of grappling yokes, the plates being engaged therein and discharged in a manner similar to the mounting and release of the bale B. 75

While there is herein shown and described the preferred embodiment of the present invention, it is nevertheless to be understood that minor changes may be made therein without departing from the spirit and scope of the invention as claimed. 80

What is claimed as new is:— 85

1. In a grappling yoke for handling wire bales, a cross head, a pair of cooperating grappling arms pivotally depending from the cross head, manually releasable devices adapted for locking the grappling arms when manually moved into their operative position, a bracket rod carried by the cross head and extending upwardly therefrom and a tapered block on the cross head beneath the bracket adapted to laterally displace the chain hook of a crane relative to the supporting bracket when the grappling yoke is released from the crane. 90

2. In a grappling yoke for handling wire bales, a cross head, a pair of cooperating grappling arms pivotally depending from the cross head, manually releasable devices adapted for locking the grappling arms when manually moved into their operative position, a bracket rod carried by the cross head and extending upwardly therefrom and a tapered block on the cross head beneath the bracket adapted to laterally displace the chain hook of a crane relative to the supporting bracket when the grappling yoke is released from the crane. 100

3. In a grappling yoke for handling wire bales, a cross head, a pair of cooperating grappling arms pivotally depending from the cross head, manually releasable devices adapted for locking the grappling arms when manually moved into their operative position, said devices including keeper loops pivoted to the ends of the cross head and said grappling arms being of angle formation with one end thereof positioned for engagement by the keeper loops when in operative position. 110

4. In a grappling yoke for handling wire bales, a cross head, a pair of cooperating grappling arms pivotally depending from the cross head, manually releasable devices adapted for locking the grappling arms when manually moved into their operative position, said devices including keeper loops 120

5 pivoted to the ends of the cross head and said grappling arms being of angle formation with one end thereof positioned for engagement by the keeper loops when in operative position.

6. 5. In a grappling yoke for handling wire bales, a cross head, a pair of cooperating grappling arms pivotally depending from the cross head, manually releasable devices 10 adapted for locking the grappling arms when manually moved into their operative position, said devices including keeper loops pivoted to the ends of the cross head, said grappling arms being of angle formation 15 with one end thereof positioned for engagement by the keeper loops when in operative position, the cross head embodying spaced side bars, a spacing block at each end thereof and upwardly directed extensions on the 20 spacing blocks upon which the keeper loops are pivotally mounted.

7. 6. In a grappling yoke for handling wire bales, a cross head, a pair of cooperating grappling arms pivotally depending from 25 the cross head, manually releasable devices

adapted for locking the grappling arms when manually moved into their operative position, said devices including keeper loops pivoted to the ends of the cross head, said grappling arms being of angle formation 30 with one end thereof positioned for engagement by the keeper loops when in operative position, the cross head embodying spaced side bars, a spacing block at each end thereof and upwardly directed extensions on the 35 spacing blocks upon which the keeper loops are pivotally mounted.

8. 7. In a grappling yoke, a cross head, grappling means carried by said head, a crane hook engaging member carried by 40 the cross head and projecting upwardly therefrom, and means carried by the cross head below the aforesaid member adapted for laterally displacing the crane hook when lowered relative to the said member to prevent engagement of the hook and member 45 when the hook is again raised.

In testimony whereof I affix my signature.

ISAAC A. RYAN.
